UNITED STATES PATENT OFFICE.

HORACE M. DOBBINS, OF PASADENA, CALIFORNIA.

LATERAL SUPPORT MONORAIL.

Application filed August 25, 1922. Serial No. 584,272.

To all whom it may concern:

Be it known that I, HORACE M. DOBBINS, a citizen of the United States, residing at Pasadena, in the county of Los Angeles and State of California, have invented new and useful Improvements in Lateral-Support Monorails, of which the following is a specification:

This invention relates to railroad apparatus and has for its object to provide a novel railroad equipment of the monorail type.

Another object of the invention is to provide a railroad equipment including track structure and vehicles of such construction as to materially reduce the cost of installation and operation, to increase the capacity, and to reduce the hazard of operation.

Another object of the invention is to provide a railway equipment consisting substantially of one main load carrying rail and a lateral support paralleling the main rail and to provide a car structure having main supporting trucks operating on the main rail; the car being provided with transversely extending means including a part running on the lateral support to aid in maintaining balance of the car and stabilizing its action.

Another object is to provide a supplementary and auxiliary special support section in cases of peculiar conditions.

A further object is to provide means for driving the lateral or extended wheel running on the lateral supporting track so as to eliminate drag upon the vehicle incident to the running of the lateral supporting means on the lateral track.

Other objects and advantages will be made manifest in the following specification of embodiments of the invention illustrated in the accompanying drawings, wherein:

Figure 1 is a vertical transverse section through a form of the railroad equipment.

Figure 2 is a detail side elevation of a form of the outboard running wheel and a driving means therefor.

Figure 3 is an end elevation of a car showing a modified arrangement of the outboard or lateral supporting means.

Figure 4 is a plan of a car and the tracks therefor.

Figure 5 is a plan of a car having double outboard track wheels and lateral arms therefor.

Figure 6 is a side elevation of one form of

car showing double wheeled trucks and a single lateral or outboard wheel.

Figure 7 is a plan showing single wheeled main trucks and a car thereon.

The broad idea of the present invention consists in providing a single main load carrying track system upon which any suitable type of railway vehicle, herein represented as a passenger car, may be supported upon a set of wheels, each of the wheels being arranged preferably substantially in tandem so as to trail upon the track, and in order to provide for the utilization of an economical substantially single railway track line I provide a lighter and less expensive form of lateral or outboard track upon which may run outboard wheels, runners or sliders attached to laterally extending means in the form of arms or a frame.

In the several views a roadbed R of any suitable material is graded and at one side of the same there is provided a substantial track sleeper or bed B on which is arranged a single continuous rail or track T of sufficient strength to form a substantial support for the vehicle.

The roadbed or right-of-way R is provided to one side of the main bed B, which may be ballasted, with an auxiliary substantially continuous track or lateral support S. The lateral support S may be of any suitable construction and may or may not be provided with a track or surface medium according to the exigencies, tracks preferably being omitted for the purpose of obtaining the desired economy of construction.

A vehicle in the form of a passenger car C is here shown as being provided with any suitable type of truck or trucks 2, each truck being shown in Figure 6 as provided with tandem wheels 3 while the trucks of Figure 7 are each provided with a single wheel 4; the wheels of all of the trucks being in tandem and, if desired, the trucks 100 may be connected to the car chassis by pivoting means or king-bolt 5 so as to permit the casting of the trucks for the obvious purpose of facilitating in making curves. Power may be transmitted to the car wheels 3 in any suitable manner as, for instance, from electric motors 6 or otherwise.

Cars adaptable for this type of construction are provided with laterally extending means such as arms or beams 8, Figure 4, 110

or a framework 9 of Figure 5, and on the outer ends or portions of these lateral supports are provided running members such as wheels 10 or runners or skids which bear upon the lateral outboard supports S.

In the several figures the laterally extending arms or frames are provided with wheels and if desired these lateral wheels may be rubber tired as at 11 Figure 1. In some cases it may be desirable to positively drive the outboard wheels 10 and means is shown in Figure 2 to accomplish that object as including a motor 12 connected to the outboard wheel 10 attached to the extending arm 8.

According to the various conditions to be met in installing a railroad of the present system the lateral supports S are arranged as most convenient or desirable and in Figure 3 the lateral support S is shown as arranged in a plane well above the plane of the main track T and in which case the lateral or outboard wheels 10 are carried by outwardly extending arms or framework 8.

The outboard support S may be arranged on either side of the car and supported in any suitable manner as is indicated in dotted lines in Figure 3 according to the contour of the right-of-way.

In certain types of installation it may be desirable to utilize as the lateral support a suspended cable S', Figure 2, and in this instance the outboard wheel or wheels 10 may be provided with sufficient cylindrical length to provide for relative change of position of the support S' as determined by the path of travel of the vehicle so that the wheel can shift transversely as to the support element S'.

This form of invention lends itself especially practical in the laying of railways along open water conduits which are constructed of cement and have lateral parallel walls spaced a considerable distance and which, because of their primary function as serving as water receivers, may extend for long distances with very small grades, and my invention enables the erection of the primary monorail supporting track on one of the side walls of the conduit or aqueduct and the utilization of the opposite side wall as a support for the outboard track S which could serve as a runway for the outboard wheel or wheels of the vehicle. This utilization of the invention is especially practical in the cases of conduits or aqueducts having dimensions of fifteen to twenty feet where it would be impractical to use standard or narrow tracks along the water conduit because of the great expense involved in making the side walls of the conduit of sufficient

width to receive the ordinarily spaced tracks.

There may be cases where it is desirable to add further stability and security in operating railroads of this type and the cars may be provided with supplementary wheels 15, these wheels being adapted to run onto supplementary guard rails 16 which would be located at intervals along the right-of-way where there would be a tendency of the vehicle to rock and lift the outboard wheel or wheels 10 from their supporting track or tracks S.

It will be understood that the primary supporting wheels 3 of the vehicle or vehicles may be so arranged with relation to the center of gravity of the vehicle body as to throw more or less of the weight of the car onto the lateral outboard wheels 10, the degree of offsetting of the center of gravity as to the vertical plane of the primary wheels 3 thus readily controlling the amount of weight imposed upon the lateral supports.

While the invention has herein been shown as in combination with rolling stock having tandem wheels and tandem truck wheels, it is to be understood that any other suitable number and arrangement of car wheels may be employed, as, for instance, standard trucks with twin pairs or with double twin pairs of wheels, or, in other words, common four-wheel trucks.

Various embodiments, modifications and variations may be resorted to within the spirit of the invention as here claimed.

What is claimed is:

1. Railroad equipment comprising, in combination, a right-of-way having a main rolling stock load carrying monorail, a substantially continuous lateral trackway paralleling the monorail, and a wheeled vehicle principally supported upon the monorail and having a laterally extending outboard supporting device running on the trackway, the said supporting device being power driven to reduce dragging tendency imparted to the vehicle while the device is running on said trackway.

2. Railroad equipment comprising, in combination, a right-of-way having a main rolling stock load carrying monorail, a substantially continuous lateral trackway paralleling the monorail, and a wheeled vehicle principally supported upon the monorail and having a laterally extending outboard supporting device running on the trackway, main and lateral wheels of the vehicle being power driven.

In testimony whereof I have signed my name to this specification.

HORACE M. DOBBINS.
